FOUR-CHANNEL MEDICAL CONDITION MONITOR

Lambert F. Lyons, 5132 White Oak Ave., Apt. 247,
Los Angeles, Calif. 91316

Filed Dec. 15, 1970, Ser. No. 26,502

Term of patent 14 years

Int. Cl. D24—01

U.S. Cl. D83—1

FIG. 3

FIG. 1 is a front isometric view of my invention illustrating the control panel;

FIG. 2 is a top plan view of the medical condition monitor shown in FIG. 1; and

FIG. 3 is a right-side view of the medical condition monitor shown in FIGS. 1 and 2.

The undisclosed rear side of the monitor unit is plane and unornamented.

I claim:

The ornamental design for a four-channel medical condition monitor, as shown and described.
